ADJUSTABLE LOUVERED PANEL

Adam D. Goettl, Phoenix, Ariz., assignor to McGraw-Edison Company, Elgin, Ill., a corporation of Delaware

Filed Apr. 23, 1959, Ser. No. 55,634

Term of patent 14 years

(Cl. D62—4)

Fig. 1

Fig. 2

Fig. 1 is a front elevational view of an adjustable louvered panel with louvers disposed in several different directions; and

Fig. 2 is an enlarged fragmentary perspective view thereof showing the louvers in detail and disposed in vertical and horizontal directions.

The panel frame is of the same substantially thickness as the louvers.

This application is a division of an earlier filed co-pending joint application Serial No. D. 43,715, filed November 9, 1956, by Adam D. Goettl, Albert B. Goettl and Edward C. Klotz, Jr. for a portable evaporative cooler.

I claim:

The ornamental design for an adjustable louvered panel, substantially as shown and described.
